(57) CLAIM

The ornamental design for a towel bar, as shown and described.

DESCRIPTION

FIG. 1 is a perspective view of a towel bar of the new design; FIG. 2 is a front elevational view of the towel bar of FIG. 1; FIG. 3 is a left side elevational view of the towel bar of FIG. 1, the right side elevational view being a mirror image thereof; and,

FIG. 4 is a top plan view of the towel bar of FIG. 1. The portions of the Figures shown in broken lines are not part of the claimed design and are for illustration only.
